UNITED STATES PATENT OFFICE.

GEORGE VAN WORMER, OF HAMILTON, OHIO.

PEN-CLAMP FOR RULING-MACHINES.

1,217,370.

Specification of Letters Patent. Patented Feb. 27, 1917.

Application filed August 21, 1916. Serial No. 115,970.

To all whom it may concern:

Be it known that I, GEORGE VAN WORMER, a citizen of the United States, and residing at Hamilton, in the county of Butler and State of Ohio, have invented new and useful Improvements in Pen-Clamps for Ruling-Machines, of which the following specification is a full disclosure.

My invention relates to a pen clamp for 10 ruling machines and is more particularly directed to that type of clamp having two pen gripping jaws, normally spring pressed apart and positively drawn together to rigidly clamp a ruling pen positioned between 15 said jaws.

The main object of my invention is to provide a clamp having a single oscillating element adapted to forcibly draw the jaws together in a pen-clamping operation.

Various other objects relate to the arrangement and combination of parts affording a very durable structure conveniently 20 disassembled for cleaning and adjusting.

The features of the invention are more 25 fully set forth in the description of the accompanying drawings, forming a part of this specification, in which:—

Figure 1 is a plan view. Fig. 2 is a plan view of one of the jaw members looking 30 at its inner surface. Fig. 3 is a similar plan view of the opposite jaw member. Fig. 4 is a section on line 4—4, Fig. 1. Fig. 5 is a right hand elevation. Fig. 6 is a section on line 6—6, Fig. 1.

The clamp comprises two rectangular sections or jaws 1, 2, the section 1 extending beyond the section 2, as at 3, to provide means for connecting the clamp to the cross beam of the ruling machine in the usual or 40 any preferred manner. Embedded in the inner surface of the section 1 is a retaining plate 4 provided at intervals with rectangular apertures through which a series of eye-plates 5 project, the base portion of said 45 eye-plates being embedded in the section 1 and shouldered as at 6—6 to securely retain the plates in position. Secured to and embedded in the outer surface of one end of the section 1 is a plate 7 which extends 50 beyond the section 1 providing a support for the adjusting or clamping screw 8. Extending laterally from the plate 7 is an eye-plate 9 similar in form to the eye-plate 5.

The section 2 has a bearing plate 10 em- 55 bedded in its outer surface and said plate and the section 2 are provided with rec-

tangular apertures, relatively spaced so as to register with the eye-plates 5 of the section 1 when the two sections are assembled. When the sections are assembled, the eye-plates 5 of the section 1 extend through the alined apertures of the section 2 and beyond the outer surface of the bearing plate 10.

An oscillating shaft or rod 11 extends 60 through the eye-plates 5 and 7 and has a flat surface 12 normally resting on the bearing plate 10. The end of the rod 11 is squared and has secured to it, an arm 13, adapted to be engaged and rocked by the 65 clamp screw 8. The clamp screw extends through a screw-threaded opening in the plate 9 and carries a lock-nut 14 to lock the screw against accidental rotation. The sections are normally held in separated relation by a pair of leaf springs 15—15 which are secured to the inner surface of the section 2 and bear against the retaining plate 4 70 of the section 1.

To clamp the pen in position between the 80 two sections or jaws, the clamp screw 8 is rotated to oscillate or rock the rod 11 which, by reason of its flattened surface engaging the bearing plate 10 of the section 2 and its rounded surface engaging the eye-pieces of 85 the section 1, will tend to force the sections together in opposition to the tension of the springs 15—15.

Having described my invention, I claim:—

1. A pen clamp for ruling machines comprising two clamp sections, means normally separating the sections, eye-plates extending from one of said sections, an oscillating element engaging through said eye-plates in operative contact with the second section, 95 and means for rocking the oscillating element to move the sections toward each other in a clamping operation.

2. A pen clamp for ruling machines comprising two clamp sections, one of said sections having transverse projections, an oscillating element intermediate the transverse projections of the one section, and an outer surface of the second section, and means for rocking said element to force the 100 two sections together.

3. A clamp for ruling machines comprising two clamp sections, eye-plates extending transversely from one of the sections, an operating rod extending through the eye-plates, and having a flat side normally engaging the outer surface of the second sec- 110

tion, and means for oscillating the rod to force the sections together.

4. A clamp for ruling machines comprising an apertured section and a second section having transverse eye-plates in registry with the apertures of the first-named section, an operating shaft positioned adjacent an outer surface of the apertured section and engaging through the eye-plates of 10 the second section, and means for oscillat-

ing the shaft to force the two sections together.

In witness whereof, I hereunto subscribe my name, as attested by the two subscribing witnesses.

GEORGE VAN WORMER.
